ATTORNEY.

grooves 21 so that the area of the bearing face of the piston is materially reduced without in any way lowering the efficient working of the piston. Oil holes 22 serve as return passages for any oil collecting in the grooves 21. The skirt portion of the piston likewise has its outer face cut away by a circumferential groove 25 to reduce friction.

Wrist pin bosses 26 are provided in the fixed wall of the assembled piston for the usual purpose of mounting the connecting rods, as will be understood.

In carrying out the method of forming the piston of the present invention, the two sections 15 are cast or otherwise shaped to the required dimension and machined as necessary. The two sections are then placed with the two edges 19 in abutting relation, while the opposite two edges are held apart by the interposition of a spacing 20 block 27. In this position the section 11 is in its maximum expanded position with respect to the section 12. The meeting edges 18 are then welded together and the reinforcing rib 24 formed. This heating serves to set the sections so that the movable section 11 can expand relative to the fixed section 12. The block 27 is now removed and the piston ready for assembly with associated parts.

In connection with the grooves 21 it should be noted that these stop short of the joint between the edges 14 and 15 so that each has a closed end to prevent leakage of oil. It will now be apparent that a complete unitary piston structure has been devised wherein a sectional structure is 35 formed into a one piece expandable piston in which the use of piston rings has been entirely eliminated. Furthermore by the present construction increased compression is obtained and since the forces acting on the piston are always 40 in the nature of a push the parts are at all times maintained in joint sealing position in so far as the head and the expandable member are concerned. It should also be noted that the novel joint sealing means formed by the tongue 45 and groove construction 16 and 18 will act to seal against oil leakage and the coagulation of oil on this tongue will gradually build up a solid joint closing barrier against loss of oil.

In the form of the invention shown in Figs. 6 50 to 11 inclusive the piston is made up, like the form heretofore described, of two separate and distinct parts welded or otherwise secured together so that one part is capable of movement relative to the other and this part is so arranged 55 and constructed as to maintain a constant pressure in opposite directions from the axis of the wrist pin. Fig. 6 illustrates the part A forming in the assembled piston the fixed part relative to which the part B, shown in Fig. 7, moves. As 60 shown in Fig. 6 the part A consists of a cylindrical head 30 formed integral with a segmental depending side wall 31 having an arc length of approximately seventy degrees. The lower portion of the wall 31 is provided with an extension 65 32 forming a true circle arc terminating at an arcuate distance C from the end of the wall 31. This extension 32 therefore provides an arcuate space 33 between its upper margin and the head 30 to receive the expandable movable element as 70 will be described. The wall 31 has a boss 34 integral therewith which is reinforced by a rib 35 extending upwardly along the face of the wall 31 and terminating as an integral part of the head 30. Diametrically opposite to the boss 34 75 is the other boss 36 for carrying the other end of

the wrist pin, this boss 36 being cast or formed integral with the extension 32. A rib 37 extends from the boss 36 to the head 30 and has its ends respectively integral with these parts. It should be noted, however, that the rib 37 is spaced from the inner wall of the extension 32 to provide a clearance 38 so that the movable or expandable part (presently to be described) is free to move without contacting the aforesaid rib 37.

As shown in Fig. 7 the part B consists of a wall 10 segment 40 having an arc length of approximately one hundred and six degrees which is integral with and depends from a segmental band 41. This band 41 is of a width to fit snugly in the arcuate space 33, and is of a length and radius 15 (when compressed to the arc of a circle) to form with the part A a complete cylindrical piston body. The free end of the band 41 is provided with a bevel 42, and the juxtaposed portion of the wall 31 is formed with a complementary 20 bevel 43.

In assembling the parts A and B the part B is fitted into the spaces provided in part A and the two abutting edges D and E are welded together so that the completed piston becomes a 25 one piece body. When so welded the wall 40 forms a continuation of the wall 31 in the space C but the length of the wall 40 is such as to leave a clearance 44 so that part B can be fully compressed when placed in an engine cylinder. When 30 assembled the piston is heat treated so that the part B is given elasticity and set eccentric to the part A to resist any pressing tending to deform it to cylindrical shape.

In order that the united parts can be finished 35 to a true cylindrical shape the band 41 is held by suitable means completely contacted into the space 33 whereby the outer circumference can be machined and ground to the proper dimensions. When so ground the band 41 is released 40 and springs to its expanded position as shown in Figs. 9, 10, and 11.

It should be noted that a transverse rib 45 is formed integral with the head 30 on its inner face and extends diametrically thereof as a part 45 of the two reinforcing ribs 35 and 37. Thus the head 30 and bosses 34 and 36 are tied together by a bridgelike construction well adapted to withstand the thrust of the piston as transmitted to the piston rod.

In the form of the invention shown in Figs. 12 50 to 17 inclusive a piston construction is illustrated for use where the two parts of the piston are of different metals and which cannot be welded together as described heretofore for other forms 55 of the invention. In other words the form of the invention here illustrated makes it possible to provide a self expanding piston wherein such metals as aluminum for one part and cast iron for the other can be associated with the advantageous results heretofore specified.

In Fig. 12 the part C consists of a cylindrical head 50 which is cast or otherwise formed integral with a cylindrical side wall 51 by means of two vertical ribs 52 and a reinforcing bridge 65 piece 53. In this connection it should be noted that the outer faces of the respective ribs 52 are spaced from the inner wall of the wall 51 in order to provide a necessary clearance, the need for which will later be explained. As will be seen 70 from Fig. 12 the head 50 is spaced vertically from the wall 51 to form an annular space for the reception of the expandable associated part D shown in Fig. 13. This part D consists of a band 54 having a width substantially that of the an- 75

nular space provided in the part C and within which it has a close snug fit against the respective abutting surfaces. This band 54 is split or divided as shown at 55—the opposed edges of 5 which are bevelled as indicated so that when the band is clamped with these faces in contact it will form a substantially complete cylindrical ring. Adjacent the split 55 one end of the band 54 is provided with two axially disposed lugs 56, each 10 of which is drilled to provide a through hole 57 for the reception of a pin 58.

In order to assemble this band 54 it is opened sufficiently to be snapped around the ribs 52 and then is brought to a position where the lugs 56 15 are aligned with like lugs 60 formed integral with the wall 51 and provided with through openings 61 to receive the aforesaid pins 58. Also the head 58 is provided with two holes 62 properly positioned to align with the holes 57 and through 20 which the fastening and assembling pins 58 can be inserted to interlock the band 54 with the part C. The pins 58 are so dimensioned as to make a driving fit with the receiving holes and thereby to all intents and purposes have the effect of a 25 complete integral joint between the band 54 and the head 58 and wall 51. As explained in connection with the other forms of the invention the band 54 is heat treated and set so that it has the required elasticity and tends to deform itself into 30 an eccentric shape to adequately grip the inner wall of a cylinder to prevent leakage past the piston. The lugs 60 as here shown are on opposite sides of one of the ribs 52 thus bringing the fixed part of the band at a rigid portion of the 35 wall 51 and allowing the major portion of the aforesaid band 54 to be free to be compressed or expanded relative to the head 58 and wall 51 in a manner well understood. As an integral part of the ribs 52 wrist pin bosses 63 are respectively 40 provided in diametrically opposed relation on the inner face of the wall 51. It will here be noted that the clearing 64 between the respective ribs 52 and the wall 51 allows for the unrestricted movement of the band 54 when in its proper assembled condition.

While only three forms are shown in which this invention may be embodied, it is to be understood that the invention is not limited to any specific construction, but might be applied to various 50 forms without departing from the spirit of the invention or the scope of the appended claims.

Having thus described my invention, I claim:—

1. A self expanding piston consisting of two segmental sections of material welded together 55 along two meeting edges, and the other meeting edges being complementary and spaced apart, a piston head on one of said sections projecting laterally to close an end of the other section, and means for mounting a wrist pin in the assembled piston.

2. A self expanding piston consisting of two segmental sections of material secured together along two meeting edges, and the other meeting edges being complementary and spaced apart, a 65 piston head on one of said sections projecting laterally to close an end of the other section, and means for mounting a wrist pin in the assembled piston.

3. A self expanding piston consisting of two 70 segmental sections of material welded together along two meeting edges, and the other meeting edges having complementary offset portions, a piston head on one of said sections projecting laterally to close an end of the other section while 75 allowing relative movement therebetween, and

means for mounting a wrist pin in the assembled piston.

4. A self expanding piston consisting of two segmental sections of material secured together along two meeting edges, and the other meeting edges having complementary offset portions, each 5 of said sections comprising a piston body part and a skirt part, a piston head on one of said sections projecting laterally to close an end of the other section while allowing relative movement 10 therebetween, each piston body part having circumferentially arranged grooves, and means for mounting a wrist pin in the assembled piston.

5. A self expanding piston consisting of two segmental sections of material secured together 15 along two meeting edges, and the other meeting edges having complementary offset portions, each of said sections comprising a piston body part having openings therethrough, and a skirt part, a piston head on one of said sections projecting 20 laterally to close an end of the other section while allowing relative movement therebetween, each piston body part having circumferentially arranged grooves communicating with said openings, and means for mounting a wrist pin in the 25 assembled piston.

6. A self expanding piston consisting of two segmental sections of material secured together along two meeting edges and the other meeting edges having complementary offset portions, each 30 of said sections comprising a piston body part and a skirt part, a piston head on one of said sections projecting laterally to close an end of the other section while allowing relative movement 35 therebetween, means to prevent oil leakage between the piston body parts, and means for mounting a wrist pin in the assembled piston.

7. A self expanding piston consisting of two segmental sections of material secured together along two meeting edges and the other meeting edges having complementary offset portions, each 40 of said sections comprising a piston body part and a skirt part, a piston head on one of said sections projecting laterally to close an end of the other section while allowing relative movement 45 therebetween, means including a tongue to prevent oil leakage between the piston body parts, and means for mounting a wrist pin in the assembled piston.

8. A self expanding piston consisting of a cylindrical head, a side wall integral with and depending from said head, a circumferentially disposed extension on said wall forming with said head an arcuate space, a band arranged to fit within said arcuate space, said band having elasticity and being normally set to maintain a pressure on an encompassing cylinder, bosses on said side wall, and means to attach one end of said band to said side wall.

9. A self expanding piston consisting of a cylindrical head, a side wall integral with and depending from said head, a circumferentially disposed extension on said wall forming with said head an arcuate space, a band arranged to fit within said arcuate space, said band having elasticity and being normally set to maintain a pressure on an encompassing cylinder, means to attach one end of said band to said side wall, axially arranged bosses formed respectively on said wall and extension, and ribs respectively connecting 55 said bosses to said head for reinforcing purposes.

10. A self expanding piston consisting of a cylindrical head, a side wall integral with and depending from said head, a circumferentially disposed extension on said wall forming with 70 75 said bosses to said head for reinforcing purposes.

said head an arcuate space, a band arranged to fit within said arcuate space, said band having elasticity and being normally set to maintain a pressure on an encompassing cylinder, means to attach one end of said band to said side wall, axially arranged bosses formed respectively on said wall and extension, and ribs respectively connecting said bosses to said head for reinforcing purposes, one of said ribs bridging said arcuate space to form a clearance for the movement of said band.

11. A self expanding piston consisting of a cylindrical head, a side wall integral with and depending from said head, a circumferentially disposed extension on said wall forming with said head an arcuate space, a split band arranged to fit within said arcuate space, said band having elasticity and being normally set to maintain a pressure on an encompassing cylinder, and means to attach one end of said band to said side wall.

12. A self expanding piston consisting of a cylindrical head, a side wall integral with and

depending from said head, a circumferentially disposed extension on said wall forming with said head an arcuate space, a split band arranged to fit within said arcuate space, said band having elasticity and being normally set eccentric to said extension, and means to attach one end of said band to said side wall.

13. A self expanding piston consisting of a cylindrical head, a side wall suspended from said head and forming a circumferential space between said head and said wall, a split band arranged to fit within said space, said band having elasticity and being normally set eccentric to the contour of said head and wall, and means to rigidly fasten one end of said band to said side wall.

14. As a new article of manufacture a unitary piston having a head, and depending side wall, said wall having wrist pin bosses and a circumferentially disposed expandible eccentric portion located between said head and said bosses.

OSCAR C. PILLAR.
